UNITED STATES PATENT OFFICE

2,543,506

GARAGE DOOR OPERATOR

Ralph W. Peters, Hollywood, Calif.

Application November 13, 1947, Serial No. 785,725

3 Claims. (Cl. 268—37)

1

This invention relates to garage doors and operators therefor.

An object of this invention is to provide an improved vehicle operated means whereby an overhead garage door may be moved to either open or closed position as the vehicle moves either toward or away from the garage.

Another object of this invention is to provide an improved spring-pressed trip mechanism which is positioned in front of the garage in a position for engagement with the wheels of the vehicle, and is so constructed and arranged that the first wheel or wheels to engage the trip mechanism will effect the movement of the door from a closed position to an open position, and the second wheel engaging the trip mechanism will have no effect on the door operation, whereas when the door has been opened the outward movement of the vehicle will cause the leading wheel to engage the trip mechanism to effect setting of the mechanism, and the following wheel will effect closing of the door. The trip mechanism is so constructed that it will be automatically set for reverse operation of the door each time it is actuated by the vehicle.

To the foregoing objects, and others which may hereinafter more fully appear, the invention consists of the novel construction, combination and arrangement of parts, as will be more specifically referred to and illustrated in the accompanying drawings, but it is to be understood that changes, variations and modifications may be resorted to which fall within the scope of the invention as claimed.

In the drawings:

Figure 1 is a detailed side elevation of a garage door operator constructed according to an embodiment of this invention.

Figure 2 is an enlarged fragmentary side elevation of a portion of the device.

Figure 3 is a fragmentary sectional view taken on the line 3—3 of Figure 2.

Figure 4 is a view similar to Figure 3, showing the latching means in latched position.

Figure 5 is a fragmentary plan view of the tripping mechanism.

Figure 6 is a sectional view taken on the line 6—6 of Figure 1.

Figure 7 is a fragmentary sectional view taken on the line 7—7 of Figure 6.

Figure 8 is a fragmentary sectional view taken on the line 8—8 of Figure 6.

Figure 9 is a fragmentary sectional view similar to Figure 8, showing the tripping mechanism in its initial set position.

2

Figure 10 is a fragmentary sectional view taken on the line 10—10 of Figure 1.

Figure 11 is a fragmentary sectional view taken on the line 11—11 of Figure 3.

Figure 12 is a fragmentary sectional view taken on the line 12—12 of Figure 8.

Figure 13 is a fragmentary side elevation of a modified form of housing for the tripping mechanism.

10 Referring to the drawings, the numeral 15 designates generally a swinging garage door which in its open position is adapted to be disposed in a substantially horizontal uppermost position as shown in full lines in Figure 1 and when in closed position is adapted to be disposed in a vertical position as shown in dotted lines in Figure 1.

The door 15 is rockably mounted on a supporting bar 16 which is secured between a pair of 20 uprights 17. A pair of divergent supporting and bracing bars 18 are fixed at their outer divergent ends to the inner side of the door 15 and are fixed at their inner convergent ends to a plate 19. The plate 19 is rockably mounted on a pivot member 25 or shaft 20 secured to the supporting bar 16. The door 15 is under spring tension from a spring 21 which is secured as at 22 to a fixed part of the garage at a point slightly above the door 15 and is fixed as at 23 to one of the supporting and bracing bars 18. The spring 21 comprises a balancing spring which is adapted to relieve the weight of the door during the swinging of the door from a vertical closed position to a horizontal open position and will hold the door 15 under tension when the latter is in its upper open position.

In order to provide for automatic opening or closing of the door 15 by movement of a vehicle along the floor 24, I have provided an elongated bar 25 which is fixed as at 26 relative to the plate 19. The bar or lever 25 has connected to the opposite ends thereof a pair of springs 27 and 28 and preferably a pair of straps or links 29 and 30, respectively, connect the upper ends of the springs 27 and 28 to the bar or lever 25 at selected points so that the lever or bar 25 will be rocked under the action of increasing the tension of one of the springs 27 or 28. The bar or lever 25 is provided with spaced holes 31 adjacent the opposite ends thereof through selected ones of which the bars or links 29 and 30 may be connected. A lower bar or lever 32 is rockably mounted as at 33 at a point below the lever 25.

The pivot member 33 is mounted on a bearing block 34 which is carried by a horizontal sup-

porting bar 35 connected between the uprights 17. The lever 32 is connected as will be herein-after described to a tripping mechanism generally designated as 36. The tripping mechanism 36 includes a U-shaped trip or crank 37 which is journaled in bearings 38 and 39 secured to the floor 24 at a point outwardly from the garage. The crank 37 includes a shaft 40 which extends horizontally to one side of the floor or entrance 24 and the crank shaft 40 has loosely mounted thereon a housing 41. The housing 41 has connected thereto adjacent the periphery thereof a clevis 42 mounted on a bolt 43 and the clevis 42 has connected thereto one end of a flexible member 43 which extends beneath a guide roller 44 and then extends into the garage and is trained under a second guide roller 45 journaled in a bearing 46 which is fixed to the floor of the garage between the uprights 17. The flexible member 43 is connected to a clevis 47 which is pivotally engaged with the lever 32 and a turnbuckle 48 is interposed between the inner end of the flexible member 43 and the clevis 47. The housing 41 has fixedly mounted therein a bolt or abutment 49 which is disposed in the path of a tripping arm 50 which is fixed on the crank shaft 40. At the time the garage door 15 is in its closed position the abutment 49 will be disposed in an uppermost position as shown in Figure 9.

In Figure 8 the abutment 49 is shown in lowermost position rearwardly of the shaft 40 which is the position to which the abutment has been moved by rotation of the housing 41 under the action of the front wheels of the vehicle striking the crank 37. When the front wheels of the vehicle which are moving inwardly of the garage strike the crank or trip member 37 the arm 50 comprising the trigger will rotate the housing 41 from the position shown in Figure 9 to the position shown in Figure 8 so that when the rear wheels pass over the crank or tripping member 37 the rear wheels will have no effect on the operation of the door or the tripping mechanism. The trigger or crank 37 is held in a substantially vertical operative position by means of a pair of springs 51 which are disposed in outwardly divergent relation being connected at their divergent ends to a bar 52 which is fixedly secured to the outer end of the crank shaft 40. The convergent ends of the springs 51 are secured to a spring tensioning eye bolt 53 which engages through a bar 54 carried by a supporting block 55. The springs 51 will thereby normally hold the trigger or crank 37 in an upright operative position in the path of the wheels of the vehicle on one side of the latter.

The trigger 37 has mounted between the parallel arms 56 thereof a sign plate 57, the plate 57 being secured to inwardly projecting lugs 58 which are carried by the inner sides of the arms 56. The bight 59 of the trigger 37 is adapted to have wound thereabout a coil spring or wire 60 which will prevent the wheels of the vehicle from climbing upwardly over the trigger and will provide for rocking of the trigger by engagement of the tires of the wheels therewith.

The door 15 is adapted to be moved to a closed position when the vehicle moves out of the garage by means of a second flexible member 61 which is connected at its inner end to a clevis 62. A turnbuckle 63 is interposed between the inner end of the flexible member 61 and the clevis 62 so that the flexible member 61 may be maintained in the desired taut condition. The clevis 62 is pivotally mounted on the lever or bar 32

5 on the opposite side of the pivot 33 from the clevis 47. The forward or outer end of the flexible member 61 is connected to an outer clevis 64 which is pivotally mounted as at 65 on the housing 41 at a point substantially diametrically opposed to the pivot 43.

In order to provide for closing of the door 15 after the vehicle has completely left the garage, I have provided a delayed tripping means associated with the tripping arm 50 whereby the housing 41 will not be rotated until the rearmost wheels of the vehicle engage the trigger 37.

A pawl 66 is rockably mounted on a pivot 67 within the housing 41 and includes a pair of pivotally connected parts 68 and 69 which are rockable relative to each other on the pivot 67. The pawl parts 68 and 69 are formed with convex inner edges 70 and 71, respectively, the edge 70 of the part 68 having a radius with the axis of the shaft 40 as a center. The convex inner edge 71 of the part 69 is disposed on a shorter radius than the radius of the edge 70 of the part 68 so that the free end of the part 69 will project inwardly into the path of the swinging of the arm 50 at the time this arm is swung downwardly and clockwise to a substantially horizontal position.

A latch member 72 is pivotally mounted on a pivot 73 in the housing 41 and is adapted to engage the pawl member 69 as shown in full lines in Figure 8 before the arm 50 has swung downwardly to a horizontal position. A spring 74 which is longitudinally bowed is fixed to the latch 72, extending from the latch 72 and having the free end thereof engaging the outer edge of the pawl member 69. A spring 75 is fixed to the pawl member 69 and extends along the outer edge of this pawl member and engages the outer edge of the pawl member 68. During the initial clockwise swinging of the arm 50 under the action of the outer or forward wheel of the vehicle the arm 50 will swing clockwise inside the convex edge 70 of the pawl member 68 and when the arm 50 is in substantially horizontal position this arm will strike the pawl member 69 and rock this member outwardly to the dotted line position shown in Figure 8.

When the arm 50 is swung upwardly by the springs 51 after the outer wheel passes over the trigger 37, the arm 50 will rock the pawl member 68 outwardly to the full line position shown in Figure 8 and the pawl member 69 will be locked against rocking under the action of the spring 74 by the outer or free end of the latch member 72 engaging on the inner concave side or edge 71 of the pawl member 69 as shown in dotted lines in Figure 8. After the arm 50 passes the pawl member 68 and assumes its normal vertical position, pawl member 68 will be swung downwardly under the action of spring 75 to the dotted line position shown in Figure 8 wherein pawl member 68 will now be disposed in the path of the subsequent swinging of the arm 50. When the rear wheel of the vehicle rocks trigger 37 a second time, arm 50 which is now locked by pawl member 68 relative to the housing 41 will cause housing 41 to rotate with the rotation or rocking of trigger 37 so that flexible member 43 will be pulled outwardly and lever 32 will be rocked downwardly to the dotted line position in Figure 1. Downward rocking of lever 32 will put spring 28 under increased tension so that the bracing members or links 18 secured to the door 15 will be rocked downwardly and forwardly.

The lever 32 is adapted to be latched in either

door opening or closing position by means of a latching bar 76 which is connected to a pivot member 77 extending through a rock lever 78. The pivot member 77 extends loosely through an elongated slot 79 formed in a vertical bar 80 and one end of the lever 78 is connected by means of a link 81 to the rock lever 32. The other end of the lever 78 is connected by means of a link 82 to the lever 25. The latch member 76 includes a forwardly offset lower portion 83 formed with an outwardly offset or bent keeper 84 and the keeper 84 is formed with an elongated slot 85 through which a latching bolt 86 loosely extends. The latching bolt 86 is horizontally slidable through the block or body 34 and is under spring tension from a spring 87 which constantly urges the bolt 86 inwardly so as to extend into the path of travel of the lever 32, as shown in Figure 4.

The latch member 76 during the initial movement of the door to closed position is adapted by reason of the movement of the lower lever 32 out of parallel relation with respect to the upper lever 25 to move the keeper 84 below the bolt 86 as shown in Figure 4 and to extend the bolt above the lever 32 to prevent any reverse pivoting thereof after the force on the crank 37 is relieved. When the door 15 has been moved to fully closed position, the two levers 25 and 32 will be disposed in substantially parallel relation and at this time the keeper or hump 84 will be engaged with the bolt 86 as shown in full lines in Figure 3.

When the door is moved from a closed to an open position, lever 32 will be initially rocked out of parallel relation with respect to lever 25, spring 27 being under increased tension, and the keeper 84 will then be initially disposed on the upper side of the bolt 86. When the door 15 is in its uppermost completely open position, latch member 76 will move downwardly to the position shown in full lines in Figure 3 wherein the keeper 84 is holding the bolt 86 retracted under maximum tension of the spring 87.

In the use and operation of this device, assuming that the door is initially in its closed position as shown in dotted lines in Figure 1, when the vehicle moves toward the garage the leading or front wheels of the vehicle will strike the trigger 37. With the door in its closed position the abutment 49 will be disposed in the position shown in Figure 9 so that the forward wheels or wheel of the vehicle will pull cable 61 forwardly and outwardly and rock lever 32 downwardly to the full line position shown in Figures 1 and 2. After the forward wheels or wheel of the vehicle pass over the trigger 37, the abutment 49 will remain in a lower rearmost position shown in Figure 8 so that the trailing or rear wheel or wheels of the vehicle will not rotate the housing 41 due to the fact that the rock arm 50 will not again engage abutment 49 as this arm is rocked rearwardly or counter-clockwise. The door 15 can be manually closed by swinging the door 15 downwardly in a clockwise direction, and when the door 15 is manually swung to a closed position it must be manually moved upwardly to an open position. However, the door 15 can be closed by the vehicle in the outward movement of the vehicle. When the vehicle moves outwardly of the garage and the door 15 is in its open position, abutment 49 will be disposed in the position shown in Figure 8. Initial forward swinging of the arm 50 will set pawl 66 by engagement of the leading wheel or wheels with the trigger 37. The trailing wheels will then engage trigger 37 and rock this trigger clockwise so that housing

41 will rotate clockwise as viewed in Figure 8, and flexible member 43 will pull lever 32 downwardly from the full line position in Figure 1 to the dotted line position. Spring 28 will thereupon be tensioned and lever 25 will rock under the tension of spring 28 so that the door 15 will be swung downwardly and forwardly to the dotted line position shown in Figure 1.

I claim:

1. In a spring-balanced swinging garage door, vehicle actuated operating means for said door comprising a rock lever, means pivotally supporting said lever between the ends thereof, operative connections between the ends of said lever 10 and said door, a rock member disposed forwardly of the garage and in the path of the vehicle wheels, a pair of flexible members connected at one end thereof to said rock lever, a rock arm fixed relative to said rock member, a housing 20 loosely coupled to said rock member, means connecting the other ends of said flexible members to diametrically opposed points of said housing, said rock arm being loosely disposed in said housing, an abutment fixed in said housing adapted for 25 engagement by said rock arm upon rocking of the latter in one direction to thereby pull one of said flexible members and effect rocking of said rock lever to door opening position, and a spring pressed pawl in said housing so constructed and 30 arranged that initial rocking of said rock arm in the opposite direction will effect an operative setting of said pawl without movement of said housing, whereby subsequent rocking of said rock arm will effect rocking of said housing with said arm 35 in said opposite direction and thereby pull the other of said flexible members to effect rocking of said rock lever to door closing position.

2. In a spring-balanced swinging garage door, vehicle actuated means for moving said door to open or closed position, said means comprising a rock lever, a pair of springs connected between the ends of said lever and said door whereby 40 rocking of said lever will effect corresponding rocking of said door, a rock member, means mounting said rock member outwardly of the garage for engagement with the wheels on one side of the vehicle, said rock member including an inverted U-shaped crank, yieldable means normally holding said crank in upright operative 45 position, a rock arm fixed relative to said rock member, a housing loosely disposed on said rock member and receiving said rock arm therein, means connecting the opposite ends of said rock lever to diametrically opposed points of said 50 housing, and a spring-pressed pawl in said housing correlated with said rock arm and adapted to effect delayed rocking of said rock lever to door closing position upon outward movement of a vehicle, and abutment means fixed in said housing 55 and engageable with said rock arm for effecting immediate rocking of said rock lever to door opening position upon inward movement of a vehicle.

3. In a spring balanced swinging garage door, 60 vehicle actuated means for moving said door to open or closed position, said means comprising a rock lever pivotally mounted intermediate the ends thereof, connecting means extending from said lever to said door, an idler lever pivotally 65 mounted in spaced relation to said rock lever, spring means connecting the ends of said rock lever to the ends of said idler lever, a rock member disposed in spaced relation to said door and in the path of movement of the vehicle, means 70 connecting said rock member to said idler lever, 75

an intermediate lever disposed between said rock lever and said idler lever, means connecting one end of said intermediate lever to said rock lever, means connecting the other end of said intermediate lever to said idler lever, vertically slidable pivot means engaging said intermediate lever intermediate the length thereof, a spring-pressed latching bolt constantly urged into the path of travel of said idler lever and adapted to block movement thereof, and latching bolt retracting means carried by said slidable pivot means and engaging said bolt for retracting said bolt when said rock lever and said idler lever are in parallel relation and adapted to release said bolt when

said rock and idler levers are out of parallel for movement of said bolt into idler lever blocking position.
